STITCHING MACHINE

William R. Spiller and Robert J. Niederhauser,
Dayton, Ohio, assignors to Harris-Seybold-Pot-
ter Company, Cleveland, Ohio, a corporation of
Delaware

Application April 21, 1943, Serial No. 483,908

15 Claims. (Cl. 1—15).

This invention relates to wire stitching machines and to such machines as disclosed in co-pending application Serial No. 472,316, filed January 14, 1943, and assigned to the same assignee as this application.

It is the principal object of the invention to provide a wire stitching machine adapted to operate at high speed to form flat, tight-fitting stitches in work material which may be partially fabricated or of such size or shape that it cannot be readily handled on the machine of said copending application.

It is a further object to provide a stitching machine of the post type in which the post is movable from a work receiving and discharging position to an operating position where the force applied during the application of the stitch develops a component acting in a direction tending to retain the post in such operative position throughout the entire operation of forming and clinching the stitch.

It is also an object to provide a post type stitching machine in which the post is readily and accurately adjustable in all directions to provide for precise cooperative relation thereof with the stitching head and with the stitch being formed in the exact location desired, a predetermined adjustment of the post being accurately maintained during the continued operation of the machine.

It is a further object to provide a stitching machine of the post type in which the post incorporates a power actuated clincher plunger and is mounted for movement from a forward work receiving and discharging position to a rearward operating position beneath a stitcher head with the actuating connections for the plunger being maintained throughout such movement.

It is a still further object to provide a post type stitcher in which the stitch may be located close to the forward face of the post with a minimum of clearance being necessary and in which the clincher mechanism is completely exposed and readily accessible for repair, replacement and adjustment.

Other objects and advantages will be apparent from the following description, the accompanying drawings, and the appended claims.

In the drawings,

Fig. 1 is a view in perspective of a stitching machine incorporating the present invention;

Fig. 2 is a broken sectional view through the base of the machine and showing the construction for pivotally supporting the post;

Fig. 3 is a broken view in front elevation with parts of the structure being broken away to show the construction of the pivotal support for the post;

Fig. 4 is a vertical sectional view on an enlarged scale through the upper end of the post showing the construction for adjusting the height of

the post and of the plunger, and the releasable mechanism for detachably securing the clincher plunger in place;

Fig. 5 is a partial front elevational view of the upper end of the post;

Fig. 6 is a detail sectional view on the line 6—6 of Fig. 5; and

Fig. 7 is a detail sectional view on the line 7—7 of Fig. 4.

Referring to the drawings which disclose a preferred embodiment of the invention, the machine is shown as having a main frame including a base portion 10, an upwardly projecting pedestal 11, and an overhanging head 12. The drive motor 14 is mounted in the rear portion of the head and has a suitable driving connection to the main shaft 15. Shaft 15 extends through the head to the front part thereof where the mechanism for forming and driving the stitches is located, the position thereof being indicated by reference numeral 16. A coil of wire 17 is mounted in a convenient location on the head and the wire feeds into the stitch forming mechanism in the usual way where it is formed into an inverted U-shaped stitch, the two legs of the stitch being driven downwardly into and through the work material received beneath the head.

For certain types of work, particularly where it is desired to apply stitches to the work material which is either partly or wholly fabricated or formed into shape and hence not in flat or sheet form where it can be handled by a stitching machine incorporating a fixed arm, it becomes desirable to utilize a machine incorporating a post, over which the work material can be received. Preferably the post is mounted for adjustable movement so that it can be withdrawn to a forward position clear of the stitcher head for receiving and discharging the work material, and returned to a rearward or operative position where the post together with the work supported thereon are moved into position directly beneath the stitching head. Such movement is conveniently effected by the pivoting of the post so that it swings forward to an inclined position where the work can be telescoped or otherwise conveniently positioned over the upper end thereof, the post being then returned with a swinging movement to its upright position where the work is supported in proper position beneath the head, for receiving the stitch.

To provide for mounting the post for this adjusting movement, the base 10 of the machine is formed at its forward end with an integral bracket portion 20 with a shaft consisting of a heavy rod 22 being passed through the spaced arms of the bracket. The shaft is suitably pinned as shown at 23 to the arms of the bracket to retain the same in fixed relation therein. The shaft extends beyond the arms of the bracket pro-

viding spaced overhanging end portions 24 at either side thereof.

The base of the post assembly comprises a yoke 26 of relatively heavy construction, being preferably of cast metal so that, along with the heavy cast base, pedestal and head construction above described, a firm and relatively quite rigid supporting structure is provided. The yoke 26 is formed with laterally projecting extensions 28 which are internally bored to provide bearings adapted to be received over the shaft ends 24, to pivotally support the yoke thereon. As will be apparent from the drawings, the two bearings thus provided for the yoke are each spaced a substantial distance laterally of the central vertical axis of the post, thereby providing a firm and rigid support for the post, capable of preventing lateral shifting and giving adequate support to the post in the course of the operation of the machine.

In order to provide for lateral adjustment of the yoke, and correspondingly of the post, the bearing members 28 are provided with end plates 30 secured to the respective bearings by means of a series of bolts 31, making it readily possible to remove the end plates for the purpose of assembling the machine. Each plate is likewise provided with a central bore which is tapped to receive an adjusting stud 32, the position of which is fixed by a lock nut 33, the stud extending inwardly to bear against a thrust bearing in the form of a ball 34 received within a tapered recess 35 formed centrally of the end of the shaft 24.

It will thus be clear that with similar bearing adjustment provided at either end of the yoke, the lateral position of the yoke with respect to the shaft and hence the base of the machine may be easily adjusted, and once having been adjusted, such adjustment will be maintained by the securing of the respective studs 32 by means of the lock nuts 33. In this way the lateral positioning of the post assembly may be accurately determined, so that the mechanism provided at the upper end of the post will be in accurate alignment with the stitching head, and having been once established, will be accurately maintained in use.

Yoke member 26 is additionally formed with a rearwardly extending part 40, preferably formed integrally therewith. This rearward extension 40 has relatively large mass, and the mass distribution is such that the center of gravity of the entire post assembly lies rearwardly of the pivot axis, in all operative positions of the post. As a result therefore, there is a normal tendency acting in the direction to move the post from its forward work receiving and discharging position rearwardly to its upright operative position, the post remaining in such upright position unless drawn forwardly by manual or some other means.

The rearward end of the extension 40 is provided with an adjustable bolt 42 which is received within a boss 43 formed immediately adjacent the end of the extension, the bolt being adapted to project through the boss into position where its head comes in contact with the face 44 of the base of the machine. Suitable locking means are provided for retaining the stud in desired position of adjustment, and it will thus be clear that the position of the stud will determine and limit the return movement of the post to its upright position. Furthermore, since the stud 42 is spaced a substantial distance away from the

axis about which the pivotal or swinging movement takes place, it provides a highly accurate control for such position of the post, enabling the machine to be set with great precision to bring the fore and aft position of the post into the desired accurate alignment with the stitching head. Again, having once been determined and adjusted, such accurate setting is maintained throughout the normal operation of the machine, the actual force placed upon the adjusting stud during operation being low because of the relatively long moment arm of the lever so provided.

Means are likewise preferably provided for locking the post against forward swinging movement, where it is desired to prevent such motion. For this purpose the bearing arm 28 of the yoke 26 is provided with a downwardly and rearwardly extending lug 50 in the lower portion of which there is mounted the adjusting bolt 52, secured by lock nut 53. A cam 54 is mounted for adjustment about shaft 55 secured to the base 10 of the machine, and an operating handle 56 is provided for rotating the shaft. The cam has a rise and a flat as shown, so that when the handle is rotated rearwardly to bring the flat opposite the head of bolt 52, swinging movement of the post assembly is permitted. However when the handle is moved forwardly so that the rise of the cam is brought opposite the head of the bolt, which is the position shown in Fig. 2, swinging movement of the post is prevented, and it is locked in its upright or operative position.

The post is shown generally at 60, comprising a generally cylindrical tubular element suitably secured to yoke 26 by means of a portion 61 of reduced diameter extending into an aperture in yoke 26 and arranged to project upwardly therefrom. As shown in Fig. 2, the center line 62 of the post, in the upright position thereof, is substantially parallel to but rearwardly displaced from the center line of the pivot axis about which the assembly pivots. Thus the vertical axis through shaft 22 is forwardly offset from the vertical axis of the post, thereby developing a component of the force applied in the formation of the stitch which acts in a clockwise direction about the shaft 22 as viewed in Figs. 1 and 2 such as to tend to retain the assembly in its upright position. Thus despite the development of substantial forces as a result of the application of the stitch to the work and the clinching thereof, there is no tendency for the post to move out of its predetermined upright operative position, but the force developed acts in a direction to retain the same in such position, the retaining force being a component of the applied force and thus increasing in relation thereto. A firm and highly satisfactory support is thus provided with the assurance that there will be no forward travel of the post during the application of the stitch thereto, nor until such operation is completed and the pressure thereof is released making it then possible to move the post assembly forwardly to discharge the work therefrom.

The post incorporates a power operated clincher mechanism for clinching the legs of the stitch. For this purpose the rod 65 is provided which is suitably journaled within the tubular post 60, and arranged to be operated vertically relative thereto. It is likewise desired to provide a driving connection for the actuation of rod 65 which will be maintained throughout the swinging and adjusting movements of the post assembly so that no disconnection is required when the post is swung forwardly to receive the work, the drive

remaining operative at all times and in condition to be actuated whenever the post occupies its upright operative position.

The drive for the rod 65 comprises a suitable cam on the driven shaft 15 which actuates a vertical pushrod 61 extending through the pedestal portion 11 of the machine, and making connection at the lower end thereof with a bell crank 68 pivotally supported at 69 in the base of the machine. Pull rod 70 secured to the opposite arm of the bell crank carries a threaded part 16 on which there are adjustably positioned the lock nuts 72 which engage one end of a spring 13, the other end of which bears against a washer 74 suitably fixed to the frame to provide an abutment. This provides a force for restoring the motion following the power actuation thereof, and tending to keep the push rod 61 normally in engagement with the cam. An adjustable limit stop 75 may likewise be provided in the base for limiting the travel of the bell crank and hence of the pull rod 70.

At its forward end, the rod 70 has connection with an additional bell crank lever 78 which is rotatably mounted on a shaft 79 which may conveniently be the same shaft 55 which supports the locking mechanism. One end of bell crank 78 is formed with an elongated slot 80 which is engaged by a pin 81 carried at the lower end of push rod 65. This slotted construction is utilized to provide for maintaining the driving connection between the push rod and the bell crank during the swinging movement of the post from one position to another and to obtain a straight line motion for rod 65.

It will be understood that upon engagement of the motor with the clutch in response to being tripped by the usual control mechanism, the main drive shaft 15 is caused to rotate which effects the simultaneous formation of the stitch by the mechanism in the stitcher head, and correlated therewith, the actuation of the vertical push rod 61, the lower pull rod 70, and through that the upwardly extending push rod 65 to secure coordinated operation of the clincher plunger in timed relation with the formation of the stitch.

In order to provide adjustment in the level at which the work is supported, as determined by the top of the post, the upper end of the post is so made as to be adjustable in height. For this purpose the upper end of post 60 is threaded as shown at 85, and receives an adjusting nut 86 thereon which bears against an upper post section 87 which is formed with a lower guiding and supporting section 88 extending downwardly internally with respect to the section 86, to guide and support the upper end portion thereon. It will be clear that by shifting the position of the nut 86, the upper level of the post section 87 may be predetermined and accurately adjusted as may be desired.

It is also desirable to provide for corresponding or independent adjustment of the level of the operating plunger, to in this way effect adjustment of the force with which the legs of the stitch are clinched. For this purpose the upper end of push rod 65 is threaded internally to receive a stud 90, a lock nut 91 being received in position to lock the stud in a predetermined position relative to the push rod, to thereby provide for raising or lowering the same to the extent desired.

The upper post section 87 is formed to receive the die blocks 93 which are removably secured

thereto by means of bolts 94, each block being supported from below by a thrust block 95 carried by the post. The construction and operation of these dies and of the clincher plunger in relation to the formation, application and clinching of the stitch is preferably similar to that described in applicants' copending application Serial No. 472,316. Cooperating with such die blocks is a clincher plunger shown at 100 working against a back plate 98, this plunger being adapted to be driven upwardly by the actuation of push rod 65, to engage the legs of the stitch, and to flatten the same against the lower side of the work to produce a strong flat clinch.

As a result of the heavy wear to which the die blocks and the clincher plunger are subjected, it is desired to make it possible to remove and replace these parts readily. As shown the die blocks may be directly removed from the front face of the post upon withdrawal of bolts 94. In order to provide for similar removal of the clincher plunger 100, it is arranged to be supported by a circular block 101 secured to the upper end of the stud 90 by means of bolt 102. The plunger 100 is formed with a plurality of symmetrically spaced apertures 103, and for the purpose of retracting the plunger following an upward clinching stroke thereof, an L-shaped bracket 104 is provided having a pin 105 which extends into the lower aperture 103. In the position shown in Fig. 4, the pin is engaged in the aperture for normal operation. It is normally retained in this relation by means of a locking bar 107 which is pivotally supported for rotation about axis 108 and held in position against the face of the bracket by a fixed wall portion 109. The end of the locking bar may be recessed to provide a seat for a ball detent 110, yieldably urged to locking position by spring 111. When the locking bar is lifted upwardly, the bracket 104 may be moved forwardly sufficiently to disengage its pin 105 from aperture 103, whereupon the plunger 100 is free and may be removed upwardly. The plunger can thus either be inverted and reinserted, or another plunger substituted, the reverse operation then providing for detachably securing the replaced plunger in proper operative position. Clearance is provided in the base of bracket 104 providing for the forward movement thereof as described without removing the same from beneath the shoulder 112 of block 101, the parts thus not being separated for a routine change in the plunger.

If desired an air passage 115 may be provided for directing a jet of air directly onto the stitch, preferably toward the lower surface of the work where the legs project through to facilitate removal of the chips as they are formed, such jet being controlled in accordance with the operating cycle of the machine to occur at the proper time.

It will thus be apparent from the above description that the present invention provides a simple and yet highly satisfactory post type machine which incorporates a power actuated clincher plunger and in which the parts are so constructed that the drive for the clincher plunger is maintained throughout all the normal movements of the post. The construction is such that the forces of reaction transmitted to the post develop a component in a direction tending to keep the post in its proper operative position, effectively preventing any tendency of the post to shift in position during the course of the formation of the stitch. Further, the position

of the post and thus of the exact location at which the stitch is formed, may be accurately adjusted and predetermined to accurately fix that position in all directions with respect to the stitcher head, thus establishing an accurate 5 relationship and one which is maintained throughout the normal operating use of the machine.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stitching machine of the character described the combination of a base, a stitcher head supported from said base, a post cooperating with said stitcher head to receive and support the work beneath said head during the application of the stitch thereto, a clincher plunger operably mounted in said post for clinching movement relative thereto, and means for pivotally supporting said post and said clincher plunger for swinging movement from a forward inoperative position to a rearward operative position directly beneath said head, the pivot axis of said supporting means being displaced with respect to the center line of said post and said clincher plunger providing a reaction force during the application of the stitch tending to retain the post in its said operative position.

2. In a stitching machine of the character described the combination of a base, a stitcher head supported from said base, a post cooperating with said stitcher head to receive and support the work during the application of the stitch thereto under the force applied by said stitcher head, a clincher plunger operably mounted in said post for clinching movement relative thereto, and means carried by said base for supporting said post and said clincher plunger for forward pivotal movement to an inoperative work receiving and discharging position and rearward movement to an operative position directly beneath and in alignment with the force applied by said stitcher head, the pivot axis of said supporting means being forwardly offset from the line of application of said force to provide for developing a force in operation tending to retain the post in its said operative position.

3. In a stitching machine of the character described the combination of a base, a stitcher head supported in predetermined fixed relation above said base, a post cooperating with said head to receive and support the work material during the application of the stitch thereto, a plunger carried by said post and movable upwardly with respect thereto to effect the clinching of the stitch, means on said base for supporting said post for movement from a forward work receiving and discharging position to a rearward operative position beneath said head, and means carried by said base for maintaining a driving connection with said plunger throughout said movement of said post.

4. In a stitching machine of the character described the combination of a base, a stitcher head supported in predetermined fixed relation above said base, a post cooperating with said head to receive and support the work material during the application of the stitch thereto, a plunger carried by said post and movable upwardly with respect thereto to effect the clinching of the stitch,

means on said base for supporting said post for movement from a forward work receiving and discharging position to a rearward operative position beneath said head, means carried by said base for maintaining a driving connection with said plunger throughout said movement of said post, and means carried by said base for locking said post to prevent said movement thereof.

5. In a stitching machine of the character described the combination of a base, a stitcher head supported in predetermined fixed relation above said base, a post cooperating with said head to receive and support the work material during the application of the stitch thereto, a plunger carried by said post and movable upwardly with respect thereto to effect the clinching of the stitch, means for pivotally supporting said post for swinging movement from a forward inclined work receiving and discharging position to an upright operative position beneath said head, means carried by said base for maintaining a driving connection with said plunger throughout said swinging movement of said post, and means for adjustably determining the limits of said swinging movement.

6. In a stitching machine of the character described the combination of a base, a stitcher head supported in predetermined fixed relation above said base, a post cooperating with said head to receive and support the work material during the application of the stitch thereto, a plunger carried by said post and movable upwardly with respect thereto to effect the clinching of the stitch, means carried by the base for pivotally supporting said post about an axis located forwardly of the center line of the stitch providing for application of the force to the post when in upright position in a direction tending to retain the post in said position, means on said base for effecting the driving of said plunger, and means for interconnecting said driving means with said plunger providing a maintained driving connection throughout the swinging movement of the post.

45. 7. In a stitching machine of the character described the combination of a base, a stitcher head supported from said base, a post cooperating with said stitcher head to receive and support the work during the application of the stitch thereto, means for pivotally supporting said post about an axis located forwardly of the center line thereof for swinging movement from a forward inoperative position to a rearward operative position directly beneath said head, a clincher plunger operably mounted in said post for clinching movement relative thereto, said post having a part movable therewith and extending rearwardly therefrom along said base in spaced relation with respect to the pivot axis, and means carried by said extended part for engaging said base at a point removed from said pivot axis to accurately determine the operative position of the upper end of said post, the center of gravity of the post assembly lying rearwardly of said pivot axis throughout said swinging movement and providing a force effective to move said post toward its said operative position.

8. A stitching machine of the character described comprising a base, a stitcher head supported in fixed relation with respect to said base, a post cooperating with said stitcher head to receive and support the work material during the application of the stitch thereto, said post being provided with a yoke having spaced arms adjacent the lower end thereof, a bearing sup-

port on said base located inwardly of said arms, means for fixedly securing said support on said base and preventing relative rotation thereof, spaced bearings carried in said support and said arms for pivotally supporting said post at spaced points laterally outwardly of said bearing support, and means for accurately adjusting the position of said post laterally with respect to said bearings to provide for predetermining the lateral position of the upper end of said post with respect to said head.

9. A stitching machine of the character described comprising a base, a stitcher head supported in fixed relation with respect to said base, a post cooperating with said stitcher head to receive and support the work material during the application of the stitch thereto, a plunger carried by said post and movable upwardly relative thereto to effect the clinching of said stitch, power actuated means for causing said upward movement of said plunger, said post being provided with a yoke having spaced arms adjacent the lower end thereof, a bearing support on said base inwardly of said arms, spaced bearing means carried in said bearing support and said arms for pivotally supporting said post from said base at spaced points laterally outwardly of said bearing support, and means for accurately adjusting the position of said post laterally with respect to said bearings to provide for predetermining the lateral position of the upper end of said post with respect to said head.

10. A stitching machine of the character described comprising a base, a stitcher head supported in fixed relation with respect to said base, a post cooperating with said stitcher head to receive and support the work material during the application of the stitch thereto, said post being provided with laterally extending portions adjacent the lower end thereof, spaced bearing means carried in said extending portions for pivotally supporting said post from said base, means for accurately adjusting the position of said post laterally with respect to said bearings to provide for predetermining the lateral position of the upper end of said post with respect to said head, a plunger carried by said post and movable upwardly relative thereto to effect the clinching of said stitch, means on said base for driving said plunger, and means for interconnecting said drive means and said plunger providing a maintained driving connection throughout the pivotal and adjusting movements of said post.

11. A stitching machine of the character described comprising a base, a stitcher head supported in fixed relation to said base, a post cooperating with said stitcher head to receive and support the work material during the application of the stitch thereto, a frame having arms extending laterally therefrom for supporting said post upon said base, a bearing support on said base inwardly between said arms, spaced bearing means carried in said laterally extending arms and said bearing support for pivotally supporting said frame and said post from said base, said frame also having a rearwardly extending part projecting above said base to a position remote from the axis of said bearing means, and adjustable means carried in said rearwardly extending part and cooperating with said base to accurately limit the pivotal movement of said post.

12. A stitching machine of the character described comprising a base, a stitcher head sup-

ported in fixed relation to said base, a post cooperating with said stitcher head to receive and support the work material during the application of the stitch thereto, a frame having arms extending laterally therefrom for supporting said post upon said base, a bearing support on said base inwardly between said arms, spaced bearing means carried in said laterally extending arms and said bearing support for pivotally supporting said frame and said post from said base, means for shifting the position of said frame with respect to said bearings to effect accurate lateral adjustment of said post with respect to said head, said frame also having a rearwardly extending part projecting above said base to a position remote from the axis of said bearing means, and additional means carried by said rearward part to accurately limit the pivotal movement of said post into operative position.

13. A stitching machine of the character described comprising a base, a stitcher head supported in fixed relation to said base, a post cooperating with said stitcher head to receive and support the work material during the application of the stitch thereto, means on said base for supporting said post providing for movement from a forward work receiving and discharging position to a rearward operative position directly beneath said head, a plunger movable upwardly in said post for effecting the clinching of the stitch, means for adjusting the vertical height of the top of said post, and additional means for adjusting the vertical relation of said plunger thereto to provide application of a predetermined clinching pressure to the stitch.

14. A stitching machine of the character described comprising a base, a stitcher head supported in fixed relation to said base, a post cooperating with said stitcher head to receive and support the work material during the application of the stitch thereto, means on said base for supporting said post providing for movement from a forward work receiving and discharging position to a rearward operative position directly beneath said head, a clincher plunger movable upwardly in said post for effecting the clinching of the stitch, a push rod for supporting and actuating said plunger adjacent the upper end of said post, means for detachably receiving said clincher plunger on said push rod, and additional means for adjusting the vertical relation of said plunger with respect to said push rod to provide application of a predetermined clinching pressure to the stitch.

15. A stitching machine of the character described comprising a base, a stitcher head supported in fixed relation to said base, a post cooperating with said stitcher head to receive and support the work material during the application of the stitch thereto, means on said base for supporting said post providing for movement from a forward work receiving and discharging position to a rearward operative position directly beneath said head, a clincher plunger movable upwardly in said post for effecting the clinching of the stitch, a push rod for supporting and actuating said plunger adjacent the upper end of said post, means for detachably receiving said clincher plunger in operative position on said push rod, and means for releasing said plunger from said receiving means providing for direct upward withdrawal and removal of said plunger.

WILLIAM R. SPILLER.

ROBERT J. NIEDERHAUSER.
